FIG. 1

INVENTOR

Charles E. Dath.
BY George J. Haught
his. ATTORNEY

UNITED STATES PATENT OFFICE.

CHARLES E. DATH, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,070,119.

Specification of Letters Patent.

Patented Aug. 12, 1913.

Application filed August 7, 1912. Serial No. 719,754

To all whom it may concern:

Be it known that I, CHARLES E. DATH, a citizen of the United States, residing in Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft yokes for railway car draft rigging.

The object of my invention is to provide a 15 draft yoke of such construction that the draft yoke and draw bar may be connected without the use of rivets, keys, or similar means.

Referring to the drawings forming a part 20 of this specification, Figure 1 is a plan view partly in horizontal section of a railway draft rigging embodying my invention. Fig. 2 is a side elevation, and Fig. 3, a plan view of one of the halves of the draft yoke.

In drawings, 4, 4 are the draft or center sills or portions of the car frame to which the draft rigging is attached, 5 an end sill, 6 a buffer block, 7, the draw bar carry iron, 8 the draw bar, 9 the draft yoke, 10 the 25 compression resisting member within the yoke, 11 and 12, the front and rear followers respectively, 13, the tie plate, 14, 14 the stop members secured to the center sills and provided with the shoulders, 15, 15 forming 30 stops for the front follower 11, and the shoulders 16, 16 forming stops for the rear follower 12.

The draw bar 8 is provided with the usual shoulders 17, 17 which are engaged by the 40 shoulders 18, 18 at the forward end of the yoke 9. Yoke 9 consists of two U members 19 and 19' in parallel arrangement side by side, each of said members consisting of an upper strap 20 and lower strap 21 joined 45 together at the rear end by the member 22 and at the forward end with the lateral flange 23. The shoulders 18 are formed by the inturning of the forward ends of the straps 20 and 21. The flanges 23 form between them and the forward portions of the straps 20 and 21 a boxlike opening within 50 which the butt 24 of the draw bar 8 is retained when the gear is in normal position. The flanges 23 are flared inwardly as illustrated in Fig. 1 of the drawings so that on

lateral movement of the draw bar the pivotal point in the draw bar's length is at the forward end of the yoke, as indicated by numeral 25 in Fig. 1. The members 19 and 19' are hinged together at their rear ends, 60 each having a perforated flange 26, the said flanges being fastened together preferably by the bolt 27 provided with the nut 28. In applying the yoke to the draw bar the yoke is opened and slipped over the butt of 65 the draw bar from the sides, the followers and compression resisting member placed within the yoke, and all is then put in position between the center sills and sustained therein by any suitable means, preferably 70 the tie plate 13. When in position between the center sills, the shoulders 15, 15, between which the forward portion of the yoke reciprocates, prevent the spreading of 75 the two members 19 and 19' which thus secures the draw bar within the hollow box-like opening of the head of the yoke. On rearward movement of the draw bar the same directly engages the follower 11 and on forward movement of the draw bar, the 80 shoulders 17 of the same engage the shoulders 18 of the yoke.

I claim:

1. A separable two-part yoke having a 85 hooded forward end provided with shoulders, a draw bar having co-acting shoulders engaging the shoulders of the yoke, cheek plates at either side of the yoke adapted to engage said head and to hold the yoke against displacement from the draw bar.

2. In a device of the class described, a 90 separable two-part yoke provided at its forward end with shoulders, a draw bar having co-acting shoulders engaging the shoulders of the yoke, cheek plates at either side of the yoke, each member of the yoke being provided with lateral plates joining the free ends of each part of the yoke together, the 95 said cheek plates being adapted to engage the said lateral plates and hold the yoke against 100 displacement from the draw bar.

3. In a device of the class described, draft sills, stop members secured thereto, a draw bar provided with shoulders, a separable two-part draft yoke comprising two U-shaped members, said members being provided with shoulders engaging the shoulders of the draw bar, each U-shaped member being provided at its forward end with 105 a lateral plate joining the free ends of the 110

U-shaped member together, the stop members being arranged at either side of said lateral plates and adapted to engage the same to hold the yoke against displacement from the draw bar.

4. In a device of the class described, draft sills, shoulders on said sills, a yoke comprising two U-shaped members arranged side by side, said yoke having a hooded forward end provided with shoulders, a draw

bar having co-acting shoulders engaging the shoulders of the yoke, the shoulders of the sills being adapted to engage the said head to hold the yoke against displacement from the draw bar.

CHARLES E. DATH.
